UNITED STATES PATENT OFFICE.

CHARLES G. NESSLER, OF NEW YORK, N. Y.

HAIR-WAVING DEVICE.

Application filed September 22, 1922. Serial No. 589,746.

This invention relates generally to devices for waving hair.

In companion application Serial No. 589,745, filed September 22, 1922, a device of this general nature is described in which there is included a strand-heating tube having improved means for closing the end of the tube adjacent the head of the person whose hair is being treated. Means for heating the tube occupied an enclosing relation to an intermediate portion of the tube and adapter tubes were arranged to be inserted in the heater tube to cause the enclosing tubes to closely fit the external dimensions of the strand and reduce the amount of air space surrounding the coiled strand to a minimum.

In the present invention provision is made for the use of a standard size heater in connection with which is used a heater tube corresponding in size to the strand to be treated rather than to the size of the bore of the heater. Special means are provided for holding the heater tube in place in the bore of the heater with the tube in contact with one side of the bore of the heater. The invention also includes closure means for the end of the tube which may be readily opened to facilitate the cooling and drying 30 of the treated strands while still in place in the tube.

Other features of the invention will be hereinafter referred to.

In the drawings, in which a preferred embodiment of the invention has been selected for illustration,

Figure 1 is a view in longitudinal section of a device embodying a part of the invention.

Figure 2 is a view in side elevation of a heater tube forming part of the device.

Figure 3 is a longitudinal sectional view of an end portion of a heater tube provided with a modified form of closure.

Figure 4 is a view in side elevation of the device shown in Figure 3.

Figure 5 is a view similar to Figure 3 showing the closure in open position.

Figure 6 is a sectional view on the line 50 6-6 of Figure 5.

Figure 7 is an enlarged sectional view taken on the line 7-7 of Figure 1.

Referring to the drawings for a more detailed description of the invention, Figure 55 1 shows an electrical heater 5 provided with

a longitudinal bore 6 in which to receive tubular elements such as is shown at 7 in which a coiled strand of hair as at 8 is inserted for the desired heat treatment.

A feature of the invention resides in the provision of a spring friction member 9 on each heater tube, by the use of which heater tubes of different sizes and relatively smaller diameter than the bore of the heater may be frictionally held in place within the heating device. By this construction I am enabled to make use of heater tubes having substantially the same internal diameter as the outside diameter of the coiled strand undergoing treatment and to employ such various sized tubes with heaters having bores of a single standard diameter.

In order to apply the heat developed by the heater device 5 to the heater tube in the most effective manner, the spring holding member 9 is mounted along one side of the tube in such a way as to hold the opposite side wall of the heater tube in direct contact with the inner surface of the heater. This arrangement reduces to a minimum the heat insulating effects of the air gap that must necessarily exist between the heater and a container tube of smaller diameter than the heater bore, in that direct conduction of the heat is had between the contacting portions of the contiguous surfaces of the engaged parts.

In order to close the end of the heater tube adjacent the scalp of the customer a closure device 10 is made use of which includes two gate members 11 and 12 having interengaging movement toward and from each other across the end of the tube. A pair of spring arms 13 removably carried by the tube normally presses the closure gate members toward each other into closing relation to the end of the tube and clamping relation to the strand of hair 8 enclosed in the heater tube. A heat insulating band or terminal member 15 formed of felt or the like prevents the transfer of heat from the heater tube to the gate members such as would cause discomfort to the customer.

In order to facilitate and hasten the cooling of the treated strand following the heating operation, a removable closure, or one that can be opened to give access between the interior of the heater tube and the atmosphere, is provided for the outer end of 110

the tube. In the form of the invention shown in Figure 1 this removable closure consists merely of a plug member 16 which may be formed of cork or any other suitable material and may be provided with spring arms 17 to assist in holding the closure plug in place. A movable ring shaped plug 18 may be mounted on the strand support 19 if desired to define a longitudinally restricted chamber section for the coiled strand.

In Figures 3, 4, 5 and 6 of the drawing a closure member is shown having the nature of a valve and adapted to be opened or closed to provide communication between the interior of the heater tube 7 and the atmosphere or to shut off such communication during the heating operation. The closure member consists of a cup-shaped member 20 having ports 21 in its side walls adapted to be moved into and out of registration with ports 22 in the wall of the heater tube. Preferably the valve or closure member 20 is movable axially or longitudinally of the heater tube and so arranged that a slight push inward will open the ports so that a minimum of manipulation of the heated tube is required to effect the opening of the ports at the end of the strand heating operation.

In the form of the invention shown in Figures 1 and 2 heat insulating material 24 may be provided on the heater tube to permit of the handling of the tube while the cork is being removed. An insulated handle portion 25 is also provided on the heater device 5 to facilitate manipulation of the device.

It will be seen that following the operation of heating the coiled strand which has been moistened with a suitable hair softening material, the outer end of the heater tube may be opened either by removal of the plug member 16 or by opening the closure valve 20 to aid in the cooling of the heater tube and its contents. It will be clear that the heater device 5 may at the same time be removed leaving the heater tube exposed on all sides to atmosphere in addition to leaving the outer end open to the air.

My present improvements are particularly adapted for the process of permanent waving of natural hair on the human head, and they serve to materially shorten the time heretofore required in this work and also to greatly lessen the discomforts which the subject has heretofore necessarily been required to undergo. My improvements also minimize the chances of injury or impairing the hair structure, which impairment is likely to occur in the heretofore practiced processes.

What I claim is:—

1. In hair waving apparatus including a heating device having a tube receiving bore, a tubular strand receiving member formed

of heat-conducting material and having a less diameter than the diameter of the bore of the heater device, and spring means carried by the tubular member and adapted to engage the inner surface of the bore to hold 70 the tubular member in place therein.

2. In hair waving apparatus including a heating device having a tube receiving bore, a tubular strand receiving member formed of heat-conducting material and having a 75 less diameter than the diameter of the bore of the heater device, and spring means carried by the tubular member on one side thereof and adapted to engage the inner surface of the bore to hold the tubular member in eccentric relation with the oppositely disposed surface of the bore.

3. In hair waving apparatus including a heating device having a tube receiving bore, a tubular strand receiving member formed 85 of heat-conducting material and having a less diameter than the diameter of the bore of the heater device, spring means carried by the tubular member and adapted to engage the inner surface of the bore to hold 90 the tubular member in place therein, removable spring actuated closure means adapted to close the inner end of the tube and grip a strand of hair enclosed by the tube, and means for opening or closing the outer 95 end of the tube.

4. In hair waving apparatus including a strand receiving heater tube, and a closure device mounted on the outer end of said heater-tube and controlling the passage of 100 air at such end and means for adjusting said closure to vary the size of the air passage.

5. In hair waving apparatus including a strand receiving heater tube, and an adjustable closure device detachably mounted on 105 the outer end of said heater tube and having capacity for adjustment to regulate the passage of air at such end.

6. In hair waving apparatus including a strand receiving heater tube having a port 110 in the outer end portion thereof, a closure member carried by the tube, said closure member being movable to open or close said port.

7. In hair waving apparatus including a 115 strand receiving heater tube having a port in the side wall near the outer extremity thereof, and a cup-shaped closure member carried by the end of the tube, said closure member being movable with relation to the tube to 120 open or close said port.

8. In hair waving apparatus including a strand receiving heater tube having a port in the side wall near the outer end thereof, and a cup-shaped closure member carried by the end of the tube, said closure member being movable axially of the tube to open or 125 close said port.

9. In hair waving apparatus including a strand receiving heater tube having a port 130

in the side wall near the end thereof, a cup-shaped closure member mounted to slide axially within the end of the tube, said closure member having a port in the side wall thereof so arranged that when the closure member is moved to its inner position the ports

will register and when moved to its outer position the ports will be out of register and the tube closed.

Signed at New York, in the county of ¹⁰ New York and State of New York, this fifteenth day of September, A. D. 1922.

CHARLES G. NESSLER.
